(57) **CLAIM**

The ornamental design for an accessory for a microscope, as
shown and described.

DESCRIPTION

FIG. 1 is a perspective view of an accessory for a microscope;

FIG. 2 is a side view thereof;

FIG. 3 is a front view thereof;

FIG. 4 is another perspective view thereof;

FIG. 5 is another perspective view thereof; and,

FIG. 6 is another perspective view thereof.

The broken lines shown in the drawings illustrate portions of
the article and form no part of the claimed design.
